ATTORNEY

UNITED STATES PATENT OFFICE.

LEE KINGSLEY, OF SYRACUSE, NEW YORK.

HOLDER FOR ADHESIVE BINDERS.

1,375,520.

Specification of Letters Patent. Patented Apr. 19, 1921.

Application filed December 29, 1919. Serial No. 348,103.

To all whom it may concern:

Be it known that I, LEE KINGSLEY, a citizen of the United States, residing at Syracuse, in the county of Onondaga and State 5 of New York, have invented a new and Improved Holder for Adhesive Binders, of which the following is a specification.

The present invention relates to holders 10 for adhesive clips or binders, such as pasters, labels and similar articles of paper or other suitable material having one side coated with an adhesive for affixing checks to bills and for other purposes to which pasters of this character may be applied.

15 A holder for maintaining a stack of collated binders in position for convenient removal and application one by one to the article or articles to which they are to be applied, without disturbing or disarranging the remaining binders on the stack, was 20 patented by me under date of September 9, 1913, No. 1,072,859; and it is the object of the present invention to provide a more simple, practical and less expensive holder than 25 that disclosed in my prior invention, and one within which a stack of binders may be more readily assembled.

To this and other ends the invention consists of certain parts and combinations of 30 parts, all of which will be hereinafter described, the novel features being pointed out in the appended claims.

The accompanying drawings illustrating the invention are as follows:—

35 Figures 1, 2 and 3 are perspective views, respectively, of the retaining member, follower block and carton or receptacle in which the binders are incased.

Fig. 4 shows in side view a stack of binders 40 as held by the retaining member before being placed in the carton.

Fig. 5 is an enlarged vertical sectional view of the holder.

Figs. 6 and 7 are top plan and front elevation views, respectively, of the assembled parts as seen in Fig. 5.

And, Fig. 8 is a perspective view of one of the binders.

In the drawings similar reference numerals refer to similar parts throughout the several views.

The binders or clips 1 are of rectangular form, made preferably of paper, and coated on one side with an adhesive. A stack of 5 these binders, adhesive sides downward, is placed upon a triangular shaped follower 2

which, in this instance, is formed up from a metal strip. The angularly disposed sides of the follower impart a similar angular inclination to the binders, whereby they are 60 not only held in more perfect alinement and stacked arrangement but the central portions thereof are presented foremost through the opening at the top of the holder.

In order to facilitate placing a stack of 65 binders in a carton 3 and, also, as a means for holding the binders so that they may be removed one at a time, I provide a U-shape retaining member preferably formed of metal and comprising a central bottom portion 4 from which extend upwardly two spring arms 5, the free ends of which are bent inwardly to form retaining flanges or abutments 6 against which the top of the stack engages in the manner clearly shown 70 in the drawings, the stack being held in abutment with such flanges against the action of a coiled spring 7 interposed between the bottom wall 4 of the retaining member and the base of the follower 2. 80

When it is desired to assemble the parts, the spring 7 is positioned and held compressed while the side arms 5 of the retaining member are sprung slightly apart to permit the follower and stack of binders 85 thereon being placed between the arms and upon the spring. The spring is then released and holds the stack of binders against the abutments 6. The parts thus assembled are placed in the carton or receptacle 3 90 which is made of paper or other suitable material. This carton has one end open and is of a depth equal to the length of the side arms 5 of the retaining member, while its cross sectional area is substantially that of 95 the retaining member when the side arms 5 of the latter are in vertical position, a sliding engagement of the retaining member in the carton being permitted. Opposite sides of the carton are provided at their upper 100 ends with ears 8 forming guards for preventing lateral displacement of the binders protruding through the space between the flanges 6 of the retaining member.

It will thus be seen that there has been 105 provided, in combination with a suitable receptacle, a very simple and inexpensively formed retaining member by means of which a stack of binders, a follower block and an operating spring may be readily 110 assembled and inserted in the carton, and that such retaining member is so formed as

to hold the stack of binders against the action of the said spring. The central portion of the stack protrudes upwardly through the space between the opposed edges of the 5 flanged abutments 6 so that binders may be easily removed, one at a time, by engaging the deflected sides of the uppermost one between the thumb and finger and exerting a slight downward pressure on the stack. 10 When thus removed the binders are partly folded and held in proper position for use, and when all of the binders have been used the retaining member may be removed from the carton and a new stack of binders inserted. 15

What I claim is:

1. In a device of the character and for the purpose described, the combination with a receptacle having one end open, of a retaining member slidably supported within 20 said receptacle and comprising a bottom portion, two oppositely positioned side members extending at substantially right angles from said bottom portion, and abutments 25 formed on the inner faces of said side members adjacent their free ends and the open end of the receptacle.

2. In a device of the character and for the purpose described, the combination with a receptacle having one end open, of a retaining member slidably supported within 30 said receptacle and comprising a bottom portion, two oppositely positioned spring side members extending at substantially right angles from said bottom portion, and 35 abutments formed on the inner faces of said side members adjacent their free ends and the open end of the receptacle.

3. In a device of the character and for the purpose described, a retaining member 40 comprising a bottom portion, two oppositely positioned spring side members extending at substantially right angles from said bottom portion, and abutments 45 formed on the inner faces of said side members adjacent their free ends; a spring pressed follower interposed between said abutments and said bottom portion for yieldably holding the articles in the retaining member against the 50 said abutments, and an open ended receptacle in which the thus assembled parts are slidably supported.

LEE KINGSLEY.
